UNITED STATES PATENT OFFICE

133,258

DESIGN FOR A COAT

Meta Merkent, New York, N. Y.

Application January 8, 1942, Serial No. 105,066

Term of patent 7 years

To all whom it may concern:

Be it known that I, Meta Merkent, a citizen of the United States, residing in the city, county, and State of New York, have invented a new, original, and ornamental Design for a Coat, of which the following is a specification, reference being had to the accompanying drawing, forming part thereof.

I claim:

The ornamental design for a coat, as shown.

META MERKENT.
